DESIGN FOR A BALANCE

Carl Louis Otto, New York, N. Y.

Application May 26, 1948, Serial No. 146,617

Term of patent 14 years

(Cl. D52—10)

To all whom it may concern:

Be it known that I, Carl Louis Otto, a citizen of the United States of America, residing in the Borough of Manhattan, city, county, and State of New York, have invented a new, original, and ornamental Design for a Balance, of which the following is a specification, reference being had to the accompanying drawings, forming part thereof, wherein:

Figure 1 is a top plan view of a balance embodying my new design with the lid open.

Fig. 2 is a front elevation of the balance shown in Fig. 1, with the lid closed.

Fig. 3 is a side elevation of the balance shown in Figs. 1 and 2, with the lid open.

I claim:

The ornamental design for a balance, as shown.

CARL LOUIS OTTO.
